UNITED STATES PATENT OFFICE.

OTTO DEMPEWOLF, OF BRUNSWICK, GERMANY, ASSIGNOR TO BREMER & BRÜCKMANN, OF BRUNSWICK, GERMANY.

MACHINE FOR HANDLING CAN-HEADS AND THE LIKE.

1,126,722.

Specification of Letters Patent.

Patented Feb. 2, 1915.

Application filed August 24, 1910. Serial No. 578,742.

To all whom it may concern:

Be it known that I, OTTO DEMPEWOLF, a citizen of Brunswick, Germany, have invented certain new and useful Improvements in Machines for Handling Can-Heads and the like, of which the following is a full, clear, and exact specification, such as will enable others skilled in the art to which it appertains to make and use the same.

10 My invention relates to a machine for packing and handling can heads so that they are in convenient condition for further operations.

15 The object of the invention is to provide a machine for automatically removing the can heads from holders where a certain operation has been performed on them and for automatically stacking the heads in suitable galleys.

20 In carrying out the invention, I provide a moving table on which the desired operation is performed on the can heads, for instance, the placing of a gasket or packing ring therein. Coacting with the table is a device 25 by which the heads are removed from the table and distributed automatically into suitable galleys or compartments. In so operating on the can heads the rotation or other movement of the table is utilized to 30 operate an automatic stop for the can heads and to enable the number of heads handled to be noted at a glance.

The invention involves various other features of importance, all of which will be 35 fully set forth hereinafter and particularly pointed out in the claims.

Reference is now had to the accompanying drawings which illustrate, as an example, the preferred embodiment of the invention.

40 In these drawings—Figure 1 is a front elevation of the machine part thereof being shown in section; Fig. 2 is a side elevation; Fig. 3 is a plan view; and Fig. 4 is an enlarged section of one of the can head hold-

45 ers.

10 indicates the table, which is here shown as mounted to turn in a horizontal plane around a vertical supporting shaft 11. The motion of the table is intermittent and may be brought about by any desired mechanism (not shown). On this table are mounted a number of head holders shown in detail in

Fig. 4 and comprising pedestals 12 having cups 14. In these cups are located two vertically movable cups 15 and 16. The cup 16 is nested within the cup 15 and both of these cups have independent motion with respect to each other and to the cup 14. Springs 17 sustain the cup 15 and springs 18 sustain the cup 16, said springs pressing on the bottoms of the cups and supported respectively by the cup 14 and cup 15. These springs are of such relative tension that normally they hold the parts as in Fig. 4, wherein the upper edge of the cup 15 is slightly above the upper edge of the cup 14 and the upper edge of the cup 16 is slightly above the upper edge of the cup 15. During the period of rest in the intermittent movement of the table 10, the holder which is aligned with the heating head 19 is brought into contact with said head.

The can head is indicated at *a* and it will be observed that its edge *a'* is crimped to produce an inverted channel extending around the edge of the head. This head is placed on the holder so that said channel receives the upper edges of the cups 15 and 16. *b* indicates the packing gasket, which is annular to correspond with the channel in the head *a* and this is placed around the cup 16 on the upper edge of the cup 15.

The heating head 19 is provided with suitable heating means (not shown) and when a head holder with the head and gasket in place thereon moves under the heating head 19 the parts will assume the position shown in Fig. 4. The heating head then moves downward and the springs 18 and 17 are compressed, the springs 18 yielding first. This causes the upper edges of the cups 15 and 16 to become coincident with each other causing the gasket *b* to be flattened or spread out. The heat of the head 19 softens the gasket and causes it to spread out in a relatively thin sheet in the bottom of the aforesaid inverted channel extending around the edge of the head *a*. The cup 14 is provided interiorly at its upper edge with an annular inwardly tapering surface 14^a; and the continued downward movement of the head *a* brings its outer wall or flange against the surface 14^a bending said flange inwardly preparatory to the operation of seaming the

head on the body of the can. This operation of the surface 14^a need not necessarily be performed at this period of the process, and is not essentially a part of the subject-matter of this application. In Fig. 3 a chute for feeding the can heads to the holders is outlined at 20. This operation as well as that of placing the gasket *b* on the holders may be performed in any desired manner without departing from the spirit of my invention. That is to say, the heads and gaskets may be manually placed on the holders or automatic mechanism may be provided for this purpose. In Fig. 3 the position of the heating head is diagrammatically indicated at 19^a. This also may be mounted and operated in any desired manner, either manually or automatically. The table is assumed to be rotating in the direction of the arrow in Fig. 3 so that it passes from the chute 20 to the heating head and thence on to the other elements of the machine as will hereinafter fully appear.

21 indicates a chute, which slants downward tangentially from the periphery of the table 10. At the receiving end of this chute curved lifting and guide fingers 22 are disposed so that as the can heads on the holders are moved from the gasket applying position at the heating head 19^a (referred to Fig. 3) they ride over the guiding fingers 22 and are caused to roll outward toward the periphery of the table, where with the aid of a guiding finger 23 said heads are tilted edgewise and dropped into the chute 21. The guiding fingers 22 are supported in any suitable manner, for example, on a brace 24, extending between the receiving end of the chute 21 and a stationary collar 40 or like member 25 on the column 11.

The chute 21 has a transversely sliding bottom 26 of graduated width corresponding to a series of pockets 27. Controlled by the transverse position of said bottom 26 the can heads will roll on edge down the chute 21 until they reach a point where the width of the bottom 26 with regard to its relative position to the chute is such that the chute is open at the bottom and no support provided for the heads, whereupon the heads must and will fall into the particular pocket below the point referred to. At the inception of the operation the bottom 26 is moved to its extreme rightward position (referring to Fig. 3) leaving the chute open at the bottom only at the extreme end pocket. The can heads therefore fall into this particular pocket. When the pocket is filled the bottom 26 is moved toward the left a sufficient distance to open the bottom of the chute at the next adjacent pocket allowing this to be filled, and so the operation proceeds until all of the pockets are filled. When the bottom 26 reaches its extreme inward or leftward position a stop 28 attached

to the upper end of the bottom enters an upper opening of the chute, preventing further movement of the can heads and continues so to do until the operation is resumed by returning the bottom 26 to its first or outward position.

The operation of the bottom 26 may, of course, be carried on manually, but it is preferred that the operation be automatic, and to this end said bottom is provided with a tang 29, which is mounted to slide horizontally with the bottom in a bearing 30. This tang has a handle 31 attached thereto for its manual operation and it also has a ratchet bar 32 adapted to be engaged by a cog 33 fixed to the ratchet wheel 34 once for each revolution for a ratchet wheel 34. To this end said cog and wheel are connected to a common shaft 35 which is suitably mounted in a vertical position at the periphery of the table 10 but in a plane below that of the table. To the underside of the table 10 is fixedly attached a cog 36 which is arranged to engage a tooth of the ratchet 34 once for each revolution of the table. The result of this arrangement is that each time the table is rotated the ratchet wheel 34 is moved one tooth and each time the ratchet wheel is rotated the ratchet bar 32 is moved one tooth. The parts are so proportionate and organized that when this movement of the ratchet bar takes place a sufficient and predetermined number of heads will have passed over the table 10 through the chute 21 to fill one of the pockets 27 and said movement of the ratchet bar brings about a movement of the chute 26 sufficient to uncover the next adjacent pocket. The number of teeth on the ratchet bar is, at least, equal to the number of pockets so that when the movement of the ratchet bar is exhausted the end of one complete operation of the machine will be marked. It readily follows that the number of heads made in this manner may be easily counted and indeed an indicating attachment may be connected to the wheel 34 or another of the moving parts by which to show the number of heads at any period in the operation.

The pockets 27 are formed by suitable partition walls preferably consisting of a continuous backing wall 37, partitions 38, separating the pockets and a removable front wall 39. These walls are disposed at a slight inclination to the vertical and the pockets formed thereby are of less width in one direction than the width of the can heads so that the heads as they stack in the pockets take overlapping inclined positions as indicated in Fig. 2. The said walls forming the pockets are preferably mounted on pivots 40 at the bottom so that upon removing the front wall 39 the walls 37 and 38 may be rocked forward or away from the other part of the machine, thus allowing the accumu-

lated heads to be dumped from the pockets into the box or other suitable storage or transporting means in which the heads may be stored or carried to the next stage of the 5 operation of the manufacture of the cans.

5 In its organized operation therefore the machine receives the heads which have been previously flanged and impresses the gaskets into the channels in the edges of the heads. 10 After this the heads are automatically lifted from the holders and turned edgewise into the chute through which they run to the pockets. Meanwhile, an automatic step by step motion in a transverse direction is imparted to the bottom 26 causing the pockets to fill successively and finally resulting in the closing of the chute against further movement of the heads therein. If desired, 15 this operation may be made to take place concurrently with the automatic or other stoppage of the table 10. To adjust the parts after again starting the motion of the table, the bottom 26 may be returned to starting position manually through the handle 31, which operation simultaneously withdraws 20 the stop 28 and allows a resumption of the movement of the heads in the chute.

Having thus described my invention, what I claim as new and desire to secure by Letters Patent of the United States, is:

30 1. In a machine for handling can heads, the combination of a movable table adapted to support can heads, means for lifting the heads from the table, a chute for receiving the heads from said means, pockets under the chute to receive the heads therefrom, means for opening the chute to the successive pockets, and devices acting in unison with the moving of the table to automatically operate said opening means, said devices comprising a rotary element operating said opening means once for each rotation of the rotary element and a part carried by the table for periodically imparting a partial movement to the rotary element.

40 2. In a machine for handling can heads, the combination of a rotating table, a relatively stationary guiding means inclining upward and outward from the position of the heads on the table whereby as the heads are engaged with said guiding means they are caused to move transversely from the table, means for receiving the heads from the guiding means, such means comprising 50 a chute, a series of pockets, a distributor for directing the heads from the chute to the pockets and means for automatically operating the distributor in unison with the table motion.

55 60 3. In a machine for handling can heads, the combination of an inclined chute, a movable bottom for said chute, the bottom being arranged, by its movement, successively to open the chute at different points along its length and pockets to receive the can heads

from the chute, said pockets respectively located at said different points along the length of the chute.

4. In a machine for handling can heads, the combination of a chute, a transversely movable bottom therefor, increasing in width toward the receiving end of the chute, whereby upon transverse movement of the bottom the chute is successively opened at different points along its length and pockets 70 to receive the can heads from the chute, the pockets respectively located at said different points along the length of the chute. 75

5. In a machine for handling can heads, the combination of a chute, a bottom for the chute, the bottom being transversely movable and increasing in width toward the receiving end of the chute, whereby upon transverse movement of the bottom the chute is successively opened at different points along its 80 length, pockets to receive the can heads from the chute, the pockets respectively located at said different points along the length of the chute, and a stop connected to operate in unison with the bottom to close the chute 85 upon the end of movement of the bottom. 90

6. In a machine for handling can heads, the combination of an inclined chute, a movable bottom for said chute, the bottom being arranged, by its movement, successively to open the chute at different points along its length and pockets to receive the can heads from the chute, the pockets respectively located at said different points along the length of the chute and a stop connected to operate in unison with the bottom 95 100 to close the chute upon the end of movement of the bottom.

7. In a machine for handling can heads, the combination of an inclined chute, a movable bottom for said chute, the bottom being arranged, by its movement, successively to open the chute at different points along its length, pockets to receive the can heads from the chute, pockets respectively located at 105 said different points along the length of the chute, means for delivering the can heads to the chute and means for automatically operating the bottom in unison with said delivery.

8. In a machine for handling can heads, the combination of a chute, a bottom for the chute, the bottom being transversely movable and having gradually increasing widths, whereby upon transverse movement 120 of the bottom the chute is successively opened at different points along its length, pockets to receive the can heads from the chute, the pockets respectively located at said different points along the length of the 125 chute, means for delivering the can heads to the chute and means for automatically operating the chute at the bottom in unison with said delivery.

9. In a machine for handling can heads, 130

the combination with delivery means of walls forming a series of pockets, one of said walls being removable to open the pockets along their length and means for hingedly mounting said pockets to facilitate dumping their contents.

5 In testimony whereof I have signed my

name to this specification in the presence of two subscribing witnesses.

OTTO DEMPEWOLF.
